UNITED STATES PATENT OFFICE.

LOUIS O. SCHUETZ AND BEN G. SHERMAN, OF WAUCONDA, ILLINOIS.

DESIGN FOR A NIGHT-LAMP CHIMNEY.

SPECIFICATION forming part of Design No. 29,061, dated July 19, 1898.

Application filed May 6, 1898. Serial No. 679,966. Term of patent 7 years.

To all whom it may concern:

Be it known that we, LOUIS O. SCHUETZ and BEN G. SHERMAN, citizens of the United States, and residents of Wauconda, in the county of 5 Lake and State of Illinois, have invented a certain new and original Design for Night-Lamp Chimneys; and we do declare the following to be a full, clear, and exact description of the invention, such as will enable others 10 skilled in the art to which it appertains to make and use the same, reference being had to the accompanying drawings, and to letters of reference marked thereon, which form a part of this specification.

15 Figure 1 of the drawings is a front elevation of our invention, and Fig. 2 is a top plan view of the same.

This invention has relation to a new and original design for night-lamp chimneys.

20 The leading feature of the design consists in the chimney, whose body portion has the form of two truncated cones united at their bases, the lower cone resting upon a cylindrical portion or base and the upper cone having an outwardly-flared crown or extension.

25 Referring to the accompanying drawings,

the letter A designates the upper truncated cone portion; B, the flared extension or crown, having a horizontal flange b at its upper edge and also a series of lateral perforations b'. 30

C is the lower inverted cone portion, and D is the cylindrical base portion. The cone portion C has at one side an opening D'. A circumferential bead or flange h marks the junction of the portions C and D. A second 35 bead or flange j marks the junction of the two cone portions, and a third bead or flange k marks the junction of the extension or crown B with the upper cone portion. The latter also has a surrounding bead i. 40

Having thus described our invention, what we claim is—

The design for a night-lamp chimney, substantially as herein shown and described.

In testimony whereof we affix our signatures in presence of two witnesses.

LOUIS O. SCHUETZ.
BEN G. SHERMAN.
